Specification for Design.

Patented Aug. 24, 1915.

Application filed April 9, 1915. Serial No. 20,353. Term of patent 14 years.

To all whom it may concern:

Be it known that I, WALTER M. WILGUS, a citizen of the United States, residing in the city of Philadelphia, county of Philadelphia, and State of Pennsylvania, have invented a new, original, and ornamental Design for an Absorbent Block, of which the following is a specification, reference being had to the accompanying drawing, forming part thereof.

In the drawings, Figure 1 is a perspective view and Fig. 2 an elevation of a block embodying my invention, which comprises a base A with a column B resting upon it.

I claim:

The ornamental design for an absorbent block, substantially as shown and described.

WALTER M. WILGUS.
